COMBINED HEAD AND FOOT GEAR CARRYING CASE

Michael W. Bamburger, 17 Wurzerstr.,
8 Munich, Germany

Filed Aug. 18, 1970, Ser. No. 24,561

Claims priority, application Germany Feb. 20, 1970

Term of patent 14 years

Int. Cl. D3—02

U.S. Cl. D87—5

FIG. 1 is a perspective view of a combined head and foot gear carrying case showing one side and end of my new design;

FIG. 2 is a plan view in a fully open condition showing the interior thereof;

FIG. 3 is a perspective view thereof in an open condition showing the insert in a raised position;

FIG. 4 is a plan view in fully open condition showing the exterior thereof; and

FIG. 5 is a side elevational view as seen from the right of FIG. 2.

I claim:

The ornamental design for a combined head and foot gear carrying case, as shown.
